UNITED STATES PATENT OFFICE.

THOMAS S. PATTERSON, OF ROSEMONT, PENNSYLVANIA, ASSIGNOR TO THE OIL AND WASTE SAVING MACHINE COMPANY, OF PHILADELPHIA, PENNSYLVANIA, A CORPORATION OF PENNSYLVANIA.

THRUST-BEARING.

987,395.

Specification of Letters Patent. Patented Mar. 21, 1911.

Application filed January 17, 1908. Serial No. 411,353.

To all whom it may concern:

Be it known that I, THOMAS S. PATTERSON, a subject of the King of Great Britain and Ireland, residing in Rosemont, Pennsylvania, have invented certain Improvements in Thrust-Bearings, of which the following is a specification.

My invention relates to certain improvements in bearings especially designed for use in centrifugal separators or washers driven by a turbine motor, and one object of my invention is to provide improved means for supporting the basket of the device without employing a step bearing.

15 In the accompanying drawings:—Figure 1, is a vertical sectional view of a centrifugal machine illustrating my invention; Fig. 2, is a perspective view of the end of the driving shaft; and Fig. 3, is an enlarged section illustrating the coupling between the driving shaft and the basket shaft of the machine.

A is the base of the machine.

B is a casing mounted upon the base and 25 provided with a cover b.

A' is a bearing extending partly into the casing B and into the base A. In this bearing is mounted a vertical shaft E carrying at its upper end the basket D. The hub d 30 of the basket is preferably made in the manner shown in Fig. 1, having a perforated wall d'.

d² is a screen suitably mounted at the periphery of the basket.

35 F is a turbine engine casing mounted in the lower portion of the base A and this casing has a bearing f for a vertical driving shaft C to which is secured the wheel C' of the turbine engine.

40 The shaft C is suspended from a ball bearing G mounted in the lower portion of the bearing A', thus dispensing with a step bearing for the shaft C in the casing F; this obviates one of the difficulties in this class of 45 apparatus.

The anti-friction bearing G in the present instance consists of two disks g g and a series of balls or rollers g' mounted in a carriage g² situated between the two disks. In 50 the upper disk g is a seat g³ for the enlarged

end c³ of the shaft C, forming in fact a ball and socket joint. The shaft is suspended from this disk and is held laterally by the bearing f as well as by a bearing in the cap a which retains the ball bearing in place. 55

The upper end of the shaft C is rounded as at c⁴ and the end of the shaft E is concaved to fit the rounded end of the shaft C and also has a transverse slot e into which extends the key e', which is secured in a slot 60 in the head of the shaft C, preferably by a transverse pin e². Thus the shaft E rests upon the head of the shaft C, which in turn is carried by the ball bearing G, and the shaft E is driven by the shaft C through the 65 key e'. The shaft E is perfectly free with the exception that it must rotate with the shaft C and it can be readily removed with the basket, if desired, without disturbing the driving shaft C. 70

I claim:—

1. The combination of a driving shaft having an enlarged and rounded head, a ball bearing consisting of upper and lower plates and intervening balls, a socket in the upper 75 plate adapted to receive the enlarged and rounded head of the said driving shaft, a driven shaft mounted above the said driving shaft and concaved at its lower end to fit over the rounded head of the driving shaft, 80 a key secured to the driving shaft, the driven shaft having a slot in which the key extends, and means for turning the driving shaft.

2. The combination of a tubular supporting structure; two plates within said structure having anti-friction elements between them; a downwardly extending shaft section supported on and extending through said two plates; a shaft supported on and extending upwardly from said shaft section; 85 with driving means connected to the downwardly extending shaft section below said bearing plates; there being between the abutting ends of said shaft and shaft section a connection including a rounded head on 90 one of said members and a socket for said head on the other member; with a key positively connecting the head and the socket. 95

3. The combination of a tubular supporting structure; two plates mounted at the 100

lower end thereof; a shaft terminating adjacent to one of said plates; balls between the plates; the lower end of the shaft and one of the plates being provided with rounded recesses; a shaft section projecting through the plates and having a head fitting said recesses; with means for operatively coupling said shaft and the shaft section.

In testimony whereof, I have signed my name to this specification, in the presence of 10 two subscribing witnesses.

THOMAS S. PATTERSON.
